SWIMMING POOL GRAB RAIL OR THE LIKE

William O. Baker, West Covina, Calif., assignor to Swim-
quip, Inc., El Monte, Calif., a corporation of California

Application November 3, 1958, Serial No. 53,265

Term of patent 14 years

(Cl. D13—7)

Fig. 1.

Fig. 2.

Fig. 3.

Figure 1 is a perspective view of a grab rail embodying my new design;

Fig. 2 is a side elevation of the grab rail; and

Fig. 3 is a front elevation of the grab rail.

I claim:

The ornamental design for a swimming pool grab rail or the like, substantially as shown.
